UNITED STATES PATENT OFFICE.

MARTIN NEWCOMER, OF NEW YORK, N. Y.

PIANO-PLAYER.

1,087,176.

Specification of Letters Patent.

Patented Feb. 17, 1914.

Application filed May 4, 1912. Serial No. 695,100.

To all whom it may concern:

Be it known that I, MARTIN NEWCOMER, a citizen of the United States, residing in the borough of Manhattan of the city of 5 New York, in the county of New York, in the State of New York, have invented certain new and useful Improvements in Piano-Players, of which the following is a specification, reference being had to the accompanying drawings, which form a part hereof.

This invention relates to pneumatic piano players and player pianos in which provision is made for giving prominence to the 15 melody or theme. In one such player the theme or melody is given prominence by permitting the hammers by which the melody tones are produced, to have a maximum throw while the throw of the hammers 20 by which the accompaniment tones are produced is modified, a series of small bellows, severally under the control of the performer, carrying each a section of a sectional rest rail, by which the throw of the hammers 25 is determined at the will of the performer, all of such bellows being mounted upon a movable bar so that all of the bellows may be moved together to limit the throw of the hammers, except those which are permitted 30 by the individual action of the bellows to have their full throw. Such an arrangement, that is, an arrangement in which the whole series of small bellows are mounted upon a movable bar, is not altogether satisfactory and it is the object of this invention 35 to provide means by which the action of the devices which produce the accompaniment tones may be modified without requiring the several bellows to be mounted upon a movable bar or to be movable as a series, while the devices which produce the theme or melody tones are permitted to have their 40 normal action under the control of selective devices.

45 A further object of the invention is to provide a compensating device which will automatically modify the action of the devices which produce the accompaniment tones when the vacuum is increased by hand pumping, so that the performer can control, 50 by pumping, the accent or expression of the theme or melody without increasing unduly the strength of accompaniment tones.

55 In the embodiment of the invention illustrated in the drawings the several bellows which carry the sections of the hammer rest

rail are mounted upon a fixed bar or in fixed relation to the hammers and are so arranged that when any one of the bellows is collapsed the section of the rest rail which is actuated by it is moved so as to permit the corresponding group of hammers to have their full throw and selective means are provided whereby any of such bellows can be collapsed pneumatically at the will of the performer, while independent means are provided for collapsing mechanically and to any degree all of the bellows which are not collapsed pneumatically; furthermore, in the construction shown, the compensating device comprises pneumatic actuating means connected directly with the main reservoir or bellows and adapted also to be controlled by hand, such actuating means being operatively connected with the mechanical devices which are adapted to collapse more or less the several bellows, but it will be evident that an automatic compensating device of the same general character might act through other means and independently of the manually controlled devices for regulating the throw of the hammers which produce the accompaniment tones.

The invention will be more fully explained hereinafter with reference to the accompanying drawings in which it is illustrated and in which—

Figure 1 is a view partly in elevation and partly in section of so much of the mechanism of a player as is necessary to enable 90 the invention to be understood. Fig. 2 is a view of the same in front elevation.

The tone producing devices or hammers *a* are shown as pivoted upon a supporting bar *b* in suitable relation to the strings *c* and as adapted to be actuated by suitable actuating devices *d* which may be controlled by a perforated music sheet, all as usual in piano players. In suitable relation to the hammers and strings is a fixed bar *e* upon which are mounted a series of bellows *f*, each of which is adapted to control the throw of a group of the hammers *a*, each group being shown in this case as comprising three hammers. Each bellows may be expanded in the usual manner, as by a spring *f'* and each is connected by a tube *f''* with the vacuum system of the player through a selective controlling valve indicated at *g*, whereby each bellows can be collapsed at the will of the performer. To the movable member *f³* of each bellows is secured an arm *f⁴* which car-

ries a section f^5 of the sectional rest rail against which the hammers rest in their inactive positions. As each bellows f is collapsed the corresponding section f^5 of the 5 sectional rest rail is moved away from the strings and permits the corresponding hammers to have their full throw for the purpose of producing tones of maximum intensity in proportion to the strength of the 10 vacuum. As each bellows is expanded the corresponding section f^5 of the rest rail moves toward the strings and therefore restricts the throw of the corresponding hammers and reduces the strength of the tones 15 produced. Normally, it will be understood, all of the bellows are expanded and all of the tones are subdued, but as each bellows is collapsed, at the will of the performer, the corresponding hammers have their full 20 throw of a greater throw and prominence is thereby given to the tones produced thereby.

In order that the strength of accompaniment tones or of all tones, as the composition to be performed may require, may be 25 increased above the pianissimo effect produced when the bellows f are fully expanded, means are provided for collapsing more or less the bellows f which are not collapsed by the thematic or melodic devices already 30 described. For this purpose, in the construction shown, a bar h is arranged in proximity to the movable members f' of all of the bellows f , and is arranged to be moved toward the bellows so as to collapse the bellows more or less and therefore to increase 35 more or less the throw of all of the hammers and the strength of the tones. The bar h is shown as carried by arms h' of a rock shaft h^2 , while another arm h^3 is operatively connected through suitable intermediate devices with a handle k which is suitably placed for 40 manual operation. The bar h might be subject to manual control only and be directly connected to the manually operated handle, 45 but in the arrangement shown it is subject to an automatic compensating device which, for convenience, acts through the same connections as the handle k and in fact forms a part of such connections, as will now be described.

As shown, the arm h^3 is connected by a link h^4 with one arm of the bell crank lever h^5 . The other arm of the bell crank lever h^5 is connected by a link h^6 with the relatively 55 movable member m' of a bellows m , which is itself hinged as at m^2 and has its base member m^3 connected to the handle k , so that the bellows forms a variable member in the connection between the handle k 60 and the rod h . A bracket m^4 mounted on the base member m^3 of the bellows forms a point of support for a spring m^5 , one end of which is adjustably connected to the bracket by a screw and nut m^6 , while the other is directly connected to the movable member m' .

of the bellows. The bellows is connected pneumatically, as by a pipe m^7 , with the main reservoir and bellows indicated generally at n . The spring m^5 is sufficiently stiff to hold the bellows m expanded fully 70 when the bellows as a whole is moved by a handle k , so that the bar h may be moved to collapse the several bellows f , but it yields sufficiently when the vacuum is considerably increased, by hard pumping, so as to permit the bellows m to collapse more or less and thereby to move the bar h more or less away from the bellows f and permit the same to be expanded so as to move the rest rail sections toward the strings and so restrict the 75 throw of the hammers and thus compensate for the greater energy with which the hammers would otherwise be moved toward the strings by the increased vacuum. In this manner it is possible for the skilful performer, by pumping, to accent or to give more prominence to the theme or melody without equally increasing the strength of the 80 accompaniment tones.

It will be obvious that the compensating device might be used without the manual controlling device, that the manual controlling device might be used without the compensating device, and that the compensating device might be used with other thematic 90 or melodic and accompaniment controlling devices than those shown and described herein. It will also be obvious that various changes in details of construction and arrangement might be made without departing 95 from the spirit of the invention.

I claim as my invention:—

1. In a piano player, the combination of a series of hammers, a series of bellows mounted in fixed relation to the hammers, a sectional rest rail, the several sections of which are operatively connected to the movable members of the several bellows respectively, pneumatic means to actuate one or another of said bellows to vary the range of movement of the hammers, and independent means to actuate all of the bellows not actuated by said pneumatic means to vary the throw of the remaining hammers.

2. In a piano player, the combination of a series of hammers, a series of bellows mounted in fixed relation to the hammers, a sectional rest rail, the several sections of which are operatively connected to the movable members of the several bellows respectively, pneumatic means to actuate one or another of said bellows to vary the range of movement of the hammers, and mechanical devices to actuate all of the bellows not actuated by said pneumatic means to vary the 110 throw of the remaining hammers.

3. In a piano player, the combination of a series of hammers, a series of bellows mounted in fixed relation to the hammers, a sectional rest rail, the several sections of 115

which are operatively connected to the movable members of the several bellows respectively, means acting normally to expand said bellows, selective devices whereby any of said bellows may be connected to the vacuum system and be collapsed, and independent means to collapse more or less all of the bellows not collapsed through the action of said selective devices.

10 4. In a piano player, the combination of a series of hammers, a series of bellows mounted in fixed relation to the hammers, a sectional rest rail, the several sections of which are operatively connected to the movable
15 members of the several bellows respectively, means acting normally to expand said bellows, selective devices whereby any of said bellows may be connected to the vacuum system and be collapsed, and mechanical devices to collapse more or less all of the bellows not collapsed through the action of said
20 selective devices.

5. In a piano player, the combination of a series of hammers, a series of bellows mounted in fixed relation to the hammers, a sectional rest rail, the several sections of which are operatively connected to the movable members of the several bellows respectively, means acting normally to expand said bellows, selective devices whereby any of said bellows may be connected to the vacuum system and be collapsed, a bar in operative relation with the movable members of all of the bellows, and means to move said bar to collapse the bellows.

6. In a piano player, the combination of a series of hammers, a series of bellows mounted in fixed relation to the hammers, arms secured to the movable members of the 40 hammers, a sectional rest rail, the several sections of which are carried by said arms respectively, pneumatic means to actuate one or another of said bellows to vary the range of movement of the hammers, and independent means to actuate all of the bellows not actuated by said pneumatic means to vary the throw of the remaining hammers.

7. In a piano player, the combination of a series of hammers, a series of bellows mounted in fixed relation to the hammers, arms secured to the movable members of the hammers, a sectional rest rail, the several sections of which are carried by said arms respectively, pneumatic means to actuate one or another of said bellows to vary the range of movement of the hammers, and independent mechanical devices to actuate all of the bellows not actuated by said pneumatic means to vary the throw of the remaining hammers.

8. In a piano player; the combination of a series of hammers, a series of bellows mounted in fixed relation to the hammers, arms secured to the movable members of the bellows, a sectional rest rail, the several sec-

tions of which are carried by said arms respectively, means acting normally to expand said bellows, selective devices whereby any of said bellows may be connected to the vacuum system and be collapsed, and independent mechanical devices to collapse the bellows not collapsed through the action of said selective devices.

9. In a piano player, the combination of a series of hammers, a series of bellows mounted in fixed relation to the hammers, arms secured to the movable members of the bellows, a sectional rest rail, the several sections of which are carried by said arms respectively, means acting normally to expand said bellows, selective devices whereby any of said bellows may be connected to the vacuum system and be collapsed, a bar in operative relation to the movable members of said bellows, and manually controlled devices for moving said bar to collapse more or less the bellows not collapsed through the action of said selective devices. 10. In

10. In a pneumatic piano player, the combination of a main reservoir, player pneumatics, hammers actuated thereby, bellows and connections to vary the throw of the hammers, mechanical devices to restrict the movement of said bellows, and a compensating device operated by air pressure and connected to the main reservoir to vary the action of said mechanical devices.

11. In a piano player pneumatic, the combination of a main reservoir, player pneumatics, hammers actuated thereby, a series of bellows, a sectional rest rail, the several sections of which are operatively connected to the movable members of the several bellows respectively, pneumatic means to actuate one or another of said bellows to vary the range of movement of the hammers, independent means to actuate all of the bellows not actuated by said pneumatic means to vary the throw of the remaining hammers, and a compensating device operated by air pressure and connected to the main reservoir to vary the action of said independent means. 100 105 110

12. In a pneumatic piano player, the combination of a main reservoir, player pneumatics, hammers actuated thereby, a series of bellows, a sectional rest rail, the several sections of which are operatively connected to the movable members of the several bellows respectively, pneumatic means to actuate one or another of said bellows to vary the range of movement of the hammers, mechanical devices to actuate all of the bellows not actuated by said pneumatic means to vary the throw of the remaining hammers, a handle, and connections between said handle and said mechanical devices, said connections including a bellows connected to said main reservoir.

13. In a piano player, the combination of 120

a bellows, pneumatic devices to collapse the same, a bar in operative relation to the bellows to collapse the same independently of the pneumatic devices, a handle, and connections between the handle and said bar, said connections including a bellows connected to the vacuum system.

14. In a pneumatic piano player, the combination of a bellows, pneumatic devices to collapse the same, mechanical devices to collapse said bellows independently of the pneumatic devices, a handle, link and lever connections between said handle and said mechanical devices, said connections in-

cluding a hinged bellows connected to the 15 vacuum system, the base member of the bellows being connected to said handle and the relatively movable member of the bellows being connected to said mechanical devices through said link and lever connections, and 20 a spring acting normally to expand said bellows.

This specification signed and witnessed this 1st day of May, A. D. 1912.
